The ornamental design for an interior module for an entry
lockset, as shown and described.

DESCRIPTION

FIG. 1 is a perspective view of the interior module for an
entry lockset in accordance with the present invention, the
environment being shown in broken lines for illustrative
purposes only and forming no part of the claimed design.
FIG. 2 is a perspective view similar to FIG. 1 of the present
invention.

FIG. 3 is a front elevational view of the present invention.
FIG. 4 is a top plan view of the present invention.

FIG. 5 is a bottom plan view of the present invention; and,
FIG. 6 is a right side elevational view of the present
invention, the left side being a mirror image.
